UNITED STATES PATENT OFFICE

167,083

COMBINED SERVING TRAY, GLASS CADDY, AND ICE BUCKET

Robert B. Karoff, New York, N. Y., assignor to Novelty Utilities, Inc., New York, N. Y., a corporation of New York

Application March 1, 1952, Serial No. 18,746

Term of patent 14 years

(Cl. D44—10)

To all whom it may concern:

Be it known that I, Robert B. Karoff, a citizen of the United States and a resident of New York city, county and State of New York, have invented a new, original, and ornamental Design for a Combined Serving Tray, Glass Caddy, and Ice Bucket, of which the following is a specification, reference being had to the accompanying drawing, forming a part thereof, in which:

Fig. 1 is a perspective view of a combined serving tray, glass caddy, and ice bucket, showing my new design;

Fig. 2 is a top plan view thereof; and

Fig. 3 is a front elevational view thereof.

I claim:

The ornamental design for a combined serving tray, glass caddy, and ice bucket, as shown.

ROBERT B. KAROFF.
